CYLINDER PRESS EMBOSsing AND METHOD
OF PRODUCING THE SAME

Hans Peter Otto, San Francisco, Calif.

Application August 20, 1947, Serial No. 769,753

1 Claim. (Cl. 101—401.2)

1

This invention relates to improvements in cylinder press embossing and method of producing the same.

The principal object of this invention is to provide means for embossing sheets of paper and like material on a cylinder press in contradistinction to embossing ordinarily accomplished on an embossing machine where the male die moves longitudinally or vertically against the female die to effect an embossing of paper inserted therebetween.

A further object of this invention is to provide means for embossing wherein exact registration may be accomplished on a high speed press.

A still further object is to provide means whereby prepositioned intaglio plates are used to create the matching male die in a fixed position and in registration therewith.

Other objects and advantages will be apparent during the course of the following description.

In the accompanying drawings forming a part of this specification and in which like numerals are employed to designate like parts throughout the same,

Fig. 1 is a fragmentary top plan view of a base having intaglio plates secured thereto and a portion of an overlay positioned on the plates.

Fig. 2 is a perspective view of a cylinder plate having strips of material pasted thereon and showing the manner in which these strips are peeled from the cylinder to leave a thin layer of split paper on the cylinder.

Fig. 3 is an enlarged fragmentary perspective view with a portion of the cylinder plate showing the male die formed thereon.

Fig. 4 is an enlarged cross sectional view of the cylinder plate and the male die as the same is formed when rolled over the intaglio plate.

Fig. 5 is a view similar to Fig. 4 showing the die forming an embossing in a sheet of paper.

Fig. 6 is a fragmentary portion of a printed sheet showing in dotted lines the area to be cut out.

Heretofore in the art of embossing it has been necessary to cut paper to a certain size and arrange it on the press in a certain position so that it will be fed into alignment between male and female embossing dies whereby when the two dies are pressed together the paper therebetween will be embossed.

This type of embossing requires very heavy pressure inasmuch as the entire squeeze on all of the letters, or in other words the stretching of the paper over the entire area of the die, takes

2

place at the same time and consequently required such tremendous pressure that the embossing presses break down following comparatively short runs; also, the dies are soon destroyed.

Applicant has, therefore, devised a new system of embossing wherein the same is accomplished on a rotary press in such a manner that the embossing takes place through a rolling action and only a very small area of the paper, therefore, is embossed at one time, thus relieving the excessive strain upon the press and the dies above described.

Also, with this method it has been impossible to secure proper alignment of embossing plates on the curved surface of the cylinder so that the plates would be in exact registration with the sheet of paper being run through the cylinder press.

Applicant has devised a means whereby he can locate intaglio plates upon the base plate of the press in exact alignment with any predetermined position on the sheet to be embossed, and has also devised means whereby after the plates have been properly located a male die may be formed through an offset process onto the cylinder plate carried upon the cylinder of the press, which male die will then be in exact registration with the intaglio plate or female die so that paper passed between the two dies will be embossed at a predetermined position on the plate.

In the embossing of labels, for example, it has been customary to print a group of labels, i. e., twenty labels, upon a sheet of paper and to then cut the sheets, thereby producing twenty individual labels, and to then feed these individual labels through an embossing machine. This is an expensive and very slow procedure.

With applicant's method or procedure it is possible to emboss at one operation the entire twenty labels and inasmuch as a rotary press is a speedy press it is possible to turn out large quantities of sheets of embossed labels, or any other embossed matter, at a greatly reduced cost and with greater speed and accuracy.

Applicant's invention first consists in mounting a plurality of intaglio plates 5 upon a base 6, which base is generally referred to in the trade as a "patent" base, and this base is in turn later mounted for reciprocating movement on the bed of a rotary press.

These plates 5 are initially positioned by adjustable hooks 7 in approximately the position they are to assume.

A sheet of paper which is to be embossed is

now prepared by cutting out certain areas 8 from the front side thereof, which areas correspond to certain designated printed areas which are to match with the embossing. This printed area, for example, is shown at 9. (See Fig. 6.)

After the areas 8 have been cut out, the sheet is laid upon the base in the same position that they will occupy during the embossing and secured against movement.

The plates 5 are now adjusted beneath the sheet 11 until the areas 12 of the plates are in registration with the cut out portions of the sheet 11. This might be termed a rough alignment of the plates.

The base with the plates thereon is now placed in the press where the plates will occupy the normal printing position.

Upon the cylinder of the press is positioned a metal plate 10 curved to correspond with the outer surface of the cylinder.

Upon this plate I paste a layer of parallel and abutted gummed paper strips 13, and after the entire surface of the plate has been covered all of the strips are dampened so as to cause an even adherence free of any high spots.

These strips are then allowed to dry for a short interval and are then peeled from the cylinder, as shown at "A" in Fig. 2. This peeling operation splits the paper strips, thus leaving a thin layer of paper or upstanding fibers 14 which act as a tooth for the embossing cement to be later applied.

An ink roller is now inserted in the press, the plates 5 inked and an impression taken on a duplicate of the paper which is to be embossed, thus causing an over printing on the sheet which will determine how closely the registration of the plate on the base will come to the paper to be embossed.

Each plate is now individually moved as indicated by the over-printing so that the plate will be moved into closer registration.

Further printed sheets are run through the press and an over-printing repeated until all of the plates on the press are in absolute registration.

As soon as all of the plates have been properly positioned the press is run with the plate 10 in contact with the plates 5 so that a printing is effected on the peeled strips 14, thus marking the areas where the male embossing dies are to be formed.

I now apply an embossing cement to the peeled strip surface 14 of the cylinder 10, spreading the same fairly evenly over the printed areas, as shown at 15.

I then place a thin sheet of paper 20 on the cylinder, such as an onion skin paper, overlying the cement and then rotate the cylinder in contact with the plates on the base, which action causes the cement and the paper covering to be imbedded into the intaglio of the plates and to thus form a curved male die which will be in exact registration with each plate forming a female die.

The thin sheet of paper placed over the cement prevents the cement from entering the intaglio and sticking thereto and also serves to slow up the hardening of the cement.

A sheet of printed paper which is to be embossed is now run through the press to ascertain whether the positioning of the plates and the

dies are in exact registration with the printed matter on the sheet. If not, the plate out of registration may be slightly moved and a second impression taken while the cement is still soft.

Assuming now that all of the plates have been positioned in perfect alignment and the dies formed, the press is allowed to stand for approximately a half hour so that the cement will be thoroughly hardened.

The paper overlay and the cement between the male die areas on the plate 10 is then cut away, as shown at "B" in Fig. 3, thus leaving raised male dies adhering to the surface of the plate, as shown in Fig. 3 and in cross section in Figs. 4 and 5.

In Fig. 5 I have shown a sheet of paper "C" as being embossed between the plate 5 and the die formed upon the plate 10, the rolling action taking place from left to right, and thus stretching but a small portion of the paper at a time.

The press may now be run at full speed with the result that each and every sheet will be accurately embossed with clean-cut lines and in perfect registration.

It will thus be seen that I have produced a method of embossing which will accomplish all of the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

What is claimed is:

That method of producing on a press having a reciprocating base and a cooperating rotary cylinder mating embossing dies which consists in first producing an intaglio plate corresponding to the embossing desired, securing said plate on the press base, coating the press cylinder with strips of gummed paper and allowing the same to adhere to the cylinder, stripping the paper from the cylinder whereby to leave a portion of the gum on the cylinder to form a tooth, applying soft cement on the gummed surface of the cylinder in conformable relation to the plate, operating said press and thereby causing the cement to fit into the intaglio of said plate, and allowing said cement to harden.
